BY DIRECT AND MESNE ASSIGNMENTS, TO WOODSTOCK TYPEWRITER COMPANY, OF
WOODSTOCK, ILLINOIS, A CORPORATION OF ILLINOIS.

TYPE-BAR-REBOUND SPRING.

1,215,706.

Specification of Letters Patent. Patented Feb. 13, 1917.

Application filed September 28, 1914. Serial No. 863,789.

To all whom it may concern:

Be it known that we, ALVAH C. ROEBUCK and ARTHUR J. STEINKE, citizens of the United States, residing at Woodstock, in the county of McHenry, State of Illinois, have invented certain new and useful Improvements in Type-Bar-Rebound Springs, of which the following is a specification.

This invention relates to an improvement in typewriters, and more particularly to an improved mechanism for assisting in the rebound of the type bars after impact with the paper to prevent blurring the paper.

The principal object of this invention is to provide an improved mechanism of this class which will prevent blurring of the paper and will make it possible to provide a speed mechanism for both fast and slow typewriters.

For the attainment of these ends and the accomplishment of other new and useful objects as will appear, the invention consists in the features of novelty in the construction, combination, and arrangement of the several parts generally shown in the accompanying drawings and described in the specification, but more particularly pointed out in the appended claims.

In the drawings, Figure 1 is a view from the under side of some of the parts with which the present invention co-operates, illustrating the application of the invention.

Fig. 2 is a side elevation of the same.

Fig. 3 is a plan view of the rebound spring.

Fig. 4 is a side elevation of the same, and Fig. 5 is a view of a modification.

The general construction of typewriter escapements provides that upon the movement of the type bar to printing position, a movable dog of the escapement is disengaged from the escape wheel and the escape wheel is allowed to move about one tenth (1/10) of the letter space distance, at which point it engages a non-movable dog. The other nine-tenths (9/10) of the letter space travel of the carriage takes place while the type bar is returning from the printing position.

In order to make the escapement more speedy, it has been the custom to provide for a greater movement of the carriage than one tenth (1/10), in some instances up to as much as nine tenths (9/10) of the travel, on

the movement of the type bar to the printing position, and the remaining amount of the travel to take place on the return of the type bar. The dog arranged for the purpose of accomplishing this latter type of movement, is called a speed dog. The use of a speed dog has been practical only with fast operators, for if the keys are held downward with a rather sluggish movement, the paper would slide past the face of the type and blur the printing, and so a machine thus equipped has not been suitable for both fast and slow operators. To make it possible to use a speed dog for both slow and fast operators, we provide a stiff rebound spring which is engaged slightly in advance of the point at which the type engages the paper, and this rebound spring causes the type and the type bars to be speedily drawn away from the paper immediately after contact, thus preventing blurring. It has been found necessary to have the action of the rebound spring very short, otherwise it gives what is called a hard touch to the key levers.

Referring more particularly to the drawing, a type bar segment 7 is secured to the frame 8 of a typewriter and pivoted in the segment are a plurality of type bars 9, only one of which is indicated in the drawing, each of which is moved by an operating member 10 in the well-known manner.

Pivoted in depending projections 11 behind the segment 7 is a yoke 12 to which is pivoted the rear of a frame 13 secured to the universal bar 14. The universal bar is pressed by means of a spring 15 secured to a fixed support 16 in the direction of the segment 7. The type bars are each formed with a shoulder 17 which engages the universal bar 14 and upon the movement of each type bar rearwardly moves the universal bar with it against the tension of its spring 15.

Secured to that portion of the frame 8 adjacent the yoke 12 is a rebound spring 18 in the form of a flat spiral having a projection 19 at one end, preferably the inside end. A projection 20 is formed at the rear of the yoke 12 in which an adjustable contact screw 21 is movable with a lock nut 22 for holding it in place. The contact screw is set so that the projection of the spring is not engaged until the universal bar is moved almost to the limit of its backward movement, or until

the type bars have nearly reached the printing position.

In operation, the type bars are moved to the printing position by the operating mechanism and just before impact is made with the paper the rebound spring 18 is engaged, so that immediately after the impact the type bars are caused to rebound, or are thrown quickly away from the printing position to prevent blurring. The action of this rebound spring is very short so that it does not interfere with the impact of the type bar but acts quickly to throw it from printing position.

15 A modified form is shown by Fig. 5, in which a spring receiver 23 is mounted in the frame 8 in which a plunger 24 is moved by means of a spring 25 the movement in one direction being limited by means of a 20 nut 26. A yoke 12' is provided with an adjustable contact screw 21' and the action of this form is similar to that already described, the difference being in the form of the rebound spring.

25 We claim:

1. In a typewriter, the combination with type bars, of a universal bar engaged and moved thereby, means for movably supporting said bar, and a type bar rebound spring 30 attached to the frame having one end free and spaced from but operable to engage said means when the universal bar is near the end of its stroke to return the type bars quickly from their printing position.

35 2. In a typewriter, a frame, type bars movable to a common printing position, a universal bar engaged thereby, means comprising a pivoted yoke for supporting the bar for reciprocal movement, and a spring 40 supported by the frame and free from engagement with the yoke except when the universal bar has been actuated and is near the end of the stroke.

3. In a typewriter, a frame, type bars 45 movable to a common printing position, a universal bar engaged thereby, means comprising a pivoted yoke for supporting the bar for reciprocal movement, and a spring comprising a spiral metal coil attached at 50 one end to the frame and having its other end spaced from but operative to engage the yoke for returning the type bars quickly from the printing position to prevent blurring the paper.

55 4. In a typewriter, the combination with a frame, of a plurality of pivoted type bars movable to a common printing position, a universal bar mounted for movement in the frame engaged and moved by each type bar 60 as the type bar is moved to printing position, a yoke for supporting the universal bar, and a flat spring for engaging the yoke and opposing the movement of the universal bar at one end only of its movement when 65 any one of the type bars is at or near the

printing position for quickly returning the type bar from the printing position.

5. In a typewriter, the combination with a frame, of a universal bar supported for movement in the frame, type bars movable to a common printing position and adapted to engage and move the universal bar in their movement, a spring to return the universal bar, and means comprising an additional spring secured at one end to the frame 70 and having one free end and adapted to oppose the movement of the universal bar only when any one of the type bars is near the printing position for causing the type bar to rebound quickly from the printing 75 position.

6. In a typewriter, the combination with a frame, of a pivoted yoke depending therefrom, a universal bar supported by the yoke for reciprocating movement, pivoted type 80 bars to engage the universal bar and to move it and the yoke rearwardly, means to return the universal bar, and a type bar rebound spring secured to the frame and adapted to engage the yoke when the universal bar is adjacent the end of its backward movement for quickly returning the universal bar and any one of the type bars.

7. In a typewriter, the combination with a frame, of a pivoted yoke depending therefrom, a universal bar supported by the yoke for reciprocating movement, pivoted type bars to engage the universal bar and to move it and the yoke rearwardly, means to return the universal bar, a type bar rebound 90 spring secured to the frame and adapted to engage the yoke when the universal bar is adjacent the end of its backward movement for quickly returning the universal bar and any one of the type bars, and an adjusting screw in connection with the yoke for varying the point at which the rebound spring is engaged.

8. In a typewriter, the combination with a frame, of a pivoted yoke depending therefrom, a universal bar supported by the yoke for reciprocating movement, pivoted type bars to engage the universal bar and to move it and the yoke rearwardly, means to return the universal bar, and a flat spiral 100 rebound spring secured at one end to the frame and having a projection therefrom at the other end and an adjustable contact screw in connection with the yoke for engaging the projection of the spring to 105 quickly return the universal bar and the type bars when the latter are at the printing point.

9. In a typewriter, the combination with a frame, of a pivoted yoke depending therefrom, a universal bar supported by the yoke for horizontally reciprocating motion, pivoted type bars to engage and move the universal bar rearwardly and to move the yoke adjacent the frame, an adjustable contact 115

member in connection with the yoke, and a type bar rebound spring secured to the frame and adapted to engage the contact member when the universal bar is near the end of its rearward movement.

In testimony whereof we have signed our names to this specification, in the pres-

ence of two subscribing witnesses, on this 24th day of September A. D. 1914.

ALVAH C. ROEBUCK,
ARTHUR J. STEINKE.
